UNITED STATES PATENT OFFICE.

WILLIAM T. SMITH, OF PHILADELPHIA, PENNSYLVANIA.

WOVEN FABRIC.

1,008,930.

Specification of Letters Patent. Patented Nov. 14, 1911.

Application filed April 4, 1911. Serial No. 618,882.

To all whom it may concern:

Be it known that I, WILLIAM T. SMITH, a citizen of the United States, residing in Philadelphia, Pennsylvania, have invented 5 certain Improvements in Woven Fabrics, of which the following is a specification.

My invention relates to woven fabrics, but more particularly to that class of fabrics which are adapted as floor coverings.

10 My invention consists of a "duplex" or "combination" fabric, in which each face is produced by a separate and distinct series of design-producing threads. One face of the fabric thus formed is preferably produced 15 by threads which are controlled by the jacquard, while the opposite face is formed by a chenille yarn independent of the jacquard.

One object of my invention is to allow for 20 the production of a floor covering which may have a different design on each face.

Another object is to have each face produced by an entirely different class of weave. For example, with my invention the weave 25 of one face may be made to represent a cut-pile or Axminster fabric variety, while that of the opposite face may be of the ingrain, Scotch tapestry or pro-Brussels class.

I attain these objects in the following manner, reference being had to the accompanying drawings, in which:—

Figure 1, is a view of one face of a fabric woven in accordance with my invention and illustrative of the Axminster class and design; Fig. 2, is a view of the opposite face 35 of the fabric illustrated in Fig. 1, and showing another class of fabric of different design; Fig. 3, is a diagrammatic sectional view taken through the weft adjacent the binder warp which "ties in" the chenille 40 weft; Fig. 4, is a diagrammatic sectional view taken through the weft adjacent the warp which binds the jacquard weave; Fig. 5, is a diagrammatic sectional view taken 45 through the weft, showing a modification of the "tying in" binder warps; Fig. 6, is a diagrammatic sectional view taken through the weft showing a modification of the jacquard-operated binder warp; Fig. 7, is a 50 diagrammatic sectional view taken through the weft and showing another form of "tying in" binder warp; Fig. 8, is a diagrammatic sectional view taken through the weft showing another modification of the jacquard-operated binder warp and weft; 55 and Fig. 9, is a diagrammatic sectional view taken through the weft showing certain of

the jacquard controlled warp tending to form the design on one face.

Referring to the drawings, 1 is the figured chenille weft which, when woven, produces a surface similar to a cut-pile fabric; 2, 3 and 4 are the weft which are operated by the jacquard. In the present instance the several views of drawing show these jacquard controlled weft three-ply and of 65 three colors.

As shown in Fig. 3, the chenille "tying in" warps are shown at 5 and 6; the arrangement being such that they are controlled from one beam.

70 In Fig. 4, the jacquard binder warps are shown at 7 and 8; there being eight ends to the repeat in this particular arrangement; each end repeating three up and twenty-one down for each twenty-four picks. 75 Thus the same ends of warp may be used both to bind in the weft and to act as stuffers.

In Fig. 5, the chenille binders 5^a and 6^a are controlled from two shafts and act as 80 stuffers during alternate picks of the chenille weft. In this case a chain binder 7^a, 8^a, may be employed for the jacquard-controlled portion of the fabric, as shown in Fig. 6.

85 When using the single form of "tying in", as shown in Fig. 7, I preferably lease my stuffers two and two and position the "tying in" warps between each two stuffers. By making this arrangement there is no 90 possibility of pockets being formed and the fabric will be solid.

In Fig. 8, I have shown a variation in the binding of the jacquard-controlled portion of the fabric; the binders being shown at 95 7^b, 8^b and independent stuffers at 9 and 10.

In the construction shown in Fig. 9, the warp 7^c, 8^c and 9^c tend to form the design on one face.

100 In the production of my invention, I prepare a jacquard design and cut the cards for either a two, three or more ply fabric of the pro-Brussels, jacquard tapestry, ingrain or other fiber class. The chenille color design is then prepared similar to an Oriental 105 or chenille Axminster design; the same being woven in the weft loom and cut with the ordinary chenille-cutting machine, and it is round chenille thus cut and figured that I employ as a weft. The number of shots 110 of the filling in the jacquard-controlled portion of the fabric may vary in proportion to

the number of shots of the chenille weft. For example, I may shuttle in 2, 4 or 6 shots of the jacquard-controlled weft to one of the figured chenille weft (in the several views of drawing 6 shots of the jacquard-controlled weft are inserted to one of chenille) according to the desired texture and design. The chenille binding or "tying in" warp can be controlled from either of the following sources, namely, the heddles direct, the jacquard of shafts and levers. As the design is produced "in the weave" in the jacquard-controlled portion of my fabric, in order to make the same in a three-ply filling effect, for example, I shuttle in six shots—three of ground and three of figure. This same method is followed in the construction of a two or four ply, or other combination. In the jacquard weave beautiful results can be attained by using shuttles of different color yarns and coloring the figures in with self-color effect or shade or shaded effect. The threads of the jacquard design may be composed of any suitable material such as wool or, as shown in Fig. 8, they may be composed of a strong cotton, silk or jute chenille, etc.

In the several views of drawing, I have shown the chenille wefts as "round chenille" because the same requires no turning or "combing up," although it will be understood that turned up, one sided, twisted chenille (either by hot roller or any other process) may be employed.

35 A fabric woven in accordance with my invention is reversible and capable of having designs and colors of practically unlimited variety woven on each face; each surface being of an entirely different texture. This is particularly advantageous when my fabric is in the form of a rug, as either the Axminster design face may be turned up at will or that of the jacquard weave. Thus, when one face of the rug becomes monotonous to the user, either as to design or texture, the same may be turned to present a different design and type of weave. Also as each side of the fabric is constructed to present a "wear" surface, the same is rendered extremely durable.

While I have described my improved fabric as being produced by means of the jacquard, shafts, etc., it will be understood that any method of weaving may be employed without departing from the spirit of my invention.

It will be noted that my invention consists of a fabric having one face produced by a design weave of the ingrain or jacquard tapestry class, and the opposite face of figured chenille forming a design weave of the Axminster class effect.

I claim:

1. A woven fabric especially adapted as a floor covering and having two independent

series of design producing threads, one of said series being interwoven to form a design of the Scotch, ingrain, jacquard tapestry, or pro-Brussels type on one surface; the other of said series being woven to form a design having the effect of a cut-pile fabric on the opposite surface. 70

2. A woven fabric especially adapted as a floor covering and having two independent series of design producing threads; one of said series being interwoven to form a design of the Scotch, ingrain, jacquard tapestry, or pro-Brussels type on one surface; the other series being of different colors throughout the length and forming a design on the 80 opposite surface. 75

3. A woven fabric especially adapted as a floor covering and having two independent series of design producing threads, one of said series having certain of the threads of different colors interwoven to form a design of the Scotch, ingrain, jacquard tapestry, or pro-Brussels type on one surface, the other of the series being figured throughout the length and woven to form a design having the effect of a cut pile fabric on the 90 opposite surface. 85

4. A woven fabric especially adapted as a floor covering and having a plurality of series of weft threads, one of said series comprising threads of different colors interwoven to form a surface design, the other of the said series comprising figured chenille yarn forming a design on the opposite surface. 100

5. A woven fabric especially adapted as a floor covering comprising two independent series of design producing weft threads bound together, one of said series being interwoven on one face of the fabric to produce a figured weave of the Scotch, ingrain, jacquard tapestry or pro-Brussels type, the other of the said series comprising a figured chenille yarn and woven on the opposite face of the fabric to produce a figured weave of 110 the Axminster type. 105

6. A woven fabric especially adapted as a floor covering comprising a plurality of series of design producing threads, threads for binding the series of threads together, 115 warp threads binding the threads of one of the series together, one of said series having certain threads of different colors interwoven on one face of the fabric to produce a figured weave, another of the said series comprising a figured chenille yarn and woven on the opposite face of the fabric to produce a surface of Axminster effect. 120

7. A woven fabric especially adapted as a floor covering comprising a plurality of 125 series of design producing threads, warp threads binding the said series of threads together and forming stuffers, threads binding the threads of one series together, one of said series having certain threads of differ- 130

ent colors interwoven on one face of the fabric to produce a figured weave, the other of the said series comprising a figured chenille yarn and woven on the opposite face of the fabric to produce a surface of Axminster effect.

8. As a new article of manufacture, a fabric the fabric to produce a surface of Axminster chenille and the opposite surface of a fig-

ured interwoven design of Scotch, ingrain, 10 jacquard tapestry of pro-Brussels type.

In testimony whereof, I have signed my name to this specification, in the presence of two subscribing witnesses.

Correction in Letters Patent No. 1,008,930.

It is hereby certified that in Letters Patent No. 1,008,930, granted November 14, 1911, upon the application of William T. Smith, of Philadelphia, Pennsylvania, for an improvement in "Woven Fabrics," an error appears in the printed specification requiring correction as follows: Page 3, line 8, strike out the words "the fabric to produce a surface of" and insert the syllable and words *ric having one surface of figured*; and that the said Letters Patent should be read with this correction therein that the same may conform to the record of the case in the Patent Office.

Signed and sealed this 18th day of March, A. D., 1913.

C. C. BILLINGS,

Acting Commissioner of Patents.

ent colors interwoven on one face of the fabric to produce a figured weave, the other of the said series comprising a figured chenille yarn and woven on the opposite face of the fabric to produce a surface of Axminster effect.

8. As a new article of manufacture, a fabric the fabric to produce a surface of Axminster chenille and the opposite surface of a fig-

ured interwoven design of Scotch, ingrain, 10 jacquard tapestry of pro-Brussels type.

In testimony whereof, I have signed my name to this specification, in the presence of two subscribing witnesses.
